SPRING BLADE AND RAZOR FOR SAME

Zemach Auerbach, New York, N. Y., assignor to
 Gillette Safety Razor Company, Boston, Mass.,
 a corporation of Delaware

Application August 21, 1941, Serial No. 407,716

9 Claims. (Cl. 30—57)

This invention relates to blades of the wafer type and a razor for same.

Briefly, an important object of my invention is to provide double-edged razor blades which will give better shaves, have greater resiliency, longitudinal rigidity and be inexpensive to manufacture.

More particularly, my double-edged blades contain a pair of longitudinal parallel springs fashioned from the same material as the blade.

During the clamping of my blade within the razor, the pressure upon the blade is automatically distributed evenly throughout the entire blade due to the longitudinal springs which take up any uneven or excess pressure upon the blade so that the cutting edges are maintained in straighter position.

A further object of my invention is to provide longitudinal strengthening means for the blades fashioned from the same material as the blades so that the possibility of the blade breaking at its edges is minimized.

Another object of my invention is to provide a blade and a razor therefor which has means for placing the blade in a position to be easily washed and wiped safely so that cleaning of the blade will be facilitated thus providing a sanitary blade for subsequent use.

My blades may be made of untempered steel formed and then the cutting edges tempered and sharpened, or such blades may be made of tempered steel and then the flange members and the central portion of the blade can be annealed. The process of making the blade can readily be determined upon for the type of the razor in which the blade is to be used and the result desired.

For a fuller understanding of the nature and objects of my invention reference is had to the following detailed description in connection with the accompanying drawings, in which:

Fig. 1 is a perspective view of the bottom of a double-edged razor blade.

Fig. 2 is a top view of the blade shown in Fig. 1.

Fig. 3 is a bottom view of the blade shown in Fig. 1.

Fig. 4 is an end view of the blade shown in Fig. 1.

Fig. 5 is a top view of a modified blade.

Fig. 6 is a bottom view of the blade shown in Fig. 5.

Fig. 7 is an end view of the blade shown in Fig. 5.

Fig. 8 is a top view of another modified blade.

Fig. 9 is a bottom view of the blade shown in Fig. 8.

Fig. 10 is an end view of the blade shown in Fig. 8.

Fig. 11 is a perspective view of a razor in open position.

Fig. 12 is a side view of the razor shown in Fig. 11, in closed position.

Fig. 13 is a side view of the razor in open position.

Fig. 14 is a top view of the razor in closed position.

Fig. 15 is a bottom view of the razor in closed position.

Fig. 16 is an end view of the razor showing a blade partly in position, upon the forked member, parts being broken away.

Fig. 17 is the opposite end view of the razor, showing the forked member for receiving the blade, in open position.

Referring to Figs. 1 to 4, inclusive, of the drawings, numeral 25 represents a double-edged razor blade having a pair of parallel longitudinal springs or flange members 26 cut from the central portion of the blade leaving end portion 27, 28 and creating longitudinal channels 29. The springs 26 are bent first parallel to the body of the blade as shown at 30 and then at an oblique angle to the blade as shown at 31.

Referring to Figs. 5 to 7, inclusive, blade 32 is the same as blade 25 except that the parallel longitudinal springs 33 are bent inwardly from the same material at an oblique angle to the blade creating longitudinal channels 34.

Referring to Figs. 8 to 10, inclusive, blade 35 is the same as blade 25 and blade 32 except that the parallel longitudinal springs 36 are bent inwardly at an oblique angle to blade and the ends 37 of the springs 36 are bent downwardly toward the blade creating longitudinal channels 38.

Referring to the razor shown in Figs. 11 to 17, inclusive, numeral 39 is a guard for a double-edged blade, comprising a central flat portion 40 and guard portions 41. Pivoted at 43 at one end of the guard 39 there is a forked member 42 to receive the longitudinal springs 26 of blade 25 within the channels 29. Similarly, blades 32 and 35 may be placed upon the forked member 42. A stop 52 extends beyond forked member 42 so that when member 42 is in open position, it will stop at about 90° to the guard 39. Attached to pivot 43, there is also a cap 44 arranged to cover blade 25 and forked member 42 and be snapped into position by latch 45 over one end of guard 39. Within the inside of cap 44 there

is attached a block 46 with tapered sides 47 and threaded hole 48 in the central portion thereof. Hollow handle 49 has telescoped within its central portion a screw 50 long enough to engage threaded hole 48 when cap 44 is in closed position. At the opposite end of screw 50 there is a finger knob 51 which is arranged to stop a predetermined distance below the handle 49 when screw 50 is disengaged from cap 44.

In order to use the razor, latch 45 preferably 10 with the springs facing toward flat portion 40, is snapped open and forked member 42 is moved to its 90° position to the guard 39. Blade 25 is then placed upon the forked member 42 by 15 sliding the forks of member 42 into the channels 29 of the blade so that springs 26 will hug member 42. The blade 25 and forked member 42 is then allowed to drop upon guard 39. Cap 44 is then pivoted over blade 25 and guard 39 causing block 46 to fall within opening 28 of blade 25. Latch 45 is then snapped over the end of guard 39 and knob 51 is turned so that screw 50 engages 20 threaded hole 48 and the razor is then ready for shaving.

It is obvious that various changes and modifications may be made in the different details of construction of my blades and razor without departing from the general spirit of my invention, as set forth in the appended claims.

I claim:

1. A double-edged razor blade comprising a pair of parallel longitudinal springs formed from the material of said blade, said springs being bent first parallel to the body of said blade and then at an oblique angle to said blade.

2. A double-edged razor blade comprising a pair of parallel longitudinal springs formed from the material of said blade, said springs being first bent at an oblique angle to said blade and the ends then bent downwardly toward said blade.

3. A double-edged razor blade comprising a pair of parallel longitudinal springs formed from

the material of said blade, said springs being equally distant from the longitudinal medial line of said blade, said springs being bent first parallel to the body of said blade and then at an oblique angle to said blade.

4. A double-edged razor blade comprising a pair of parallel longitudinal springs formed from the material of said blade creating a pair of longitudinal channels, said springs being bent at an oblique angle to the body of said blade.

5. A double-edged razor blade comprising a pair of parallel longitudinal springs formed from the material of said blade creating a pair of longitudinal channels, said springs being first bent at an oblique angle to said blade and the ends then bent downwardly toward said blade.

6. A double-edged razor blade comprising a pair of parallel longitudinal springs formed from the material of said blade, said springs being equally distant from the longitudinal medial line of said blade, said springs being first bent at an oblique angle to said blade and the ends then bent downwardly toward said blade.

7. A safety razor, comprising a hollow handle attached to a guard a part of a hinge at one end of said guard, a hingeable fork-shaped blade-supporting member having a part of a hinge at one end, a stop on said blade supporting member, a cap having a part of a hinge at one end, said parts of said hinge held together by a pivot pin, a threaded hole in the center of said cap, a screw through said hollow handle for tightening said cap.

8. In a safety razor, the combination of a 35 forked blade supporting member with a blade having longitudinal channels in which the tines of said supporting member fit.

9. In a safety razor, the combination of a 40 forked blade supporting member with a blade having longitudinal parallel channels in which the tines of said supporting forked member fit.

ZEMACH AUERBACH.
